[57] CLAIM

The ornamental design for a combined junction box, receptacle unit and face-plate, as shown and described.

DESCRIPTION

FIG. 1 is a front elevational view of a combined electrical junction box receptacle unit and face-plate showing my new design;

FIG. 2 is a rear elevational view thereof;

FIG. 3 is an exploded left side elevational view thereof;

FIG. 4 is an exploded right side elevational view thereof;

FIG. 5 is an exploded top plan view thereof;

FIG. 6 is an exploded bottom plan view thereof;

FIG. 7 is a front elevational view of the receptacle portion thereof, with the other portions omitted for clarity of illustration;

FIG. 8 is a front elevational view of the junction box portion thereof, with the other portions omitted for clarity of illustration;

FIG. 9 is a rear elevational view of the face-plate portion thereof, with the other portions omitted for clarity of illustration; and

FIG. 10 is a rear elevational view of the receptacle portion thereof, with the other portions omitted for clarity of illustration.
